UNITED STATES PATENT OFFICE.

JOSEPH A. PATTERSON, OF WAYNESBURG, PENNSYLVANIA.

RAIL-JOINT.

1,273,660.

Specification of Letters Patent.

Patented July 23, 1918.

Application filed March 26, 1917, Serial No. 157,437. Renewed December 21, 1917. Serial No. 208,323.

To all whom it may concern:

Be it known that I, JOSEPH A. PATTERSON, a citizen of the United States, and resident of Waynesburg, in the county of Greene 5 and State of Pennsylvania, have invented certain new and useful Improvements in Rail-Joints, of which the following is a specification.

This invention relates to rail joints and 10 has more especial reference to an improved type of scarf joint.

The invention has for its dominant object to provide a rail joint, wherein the abutting ends of the rail sections are so formed as to 15 permit interlocking thereof in a manner to prevent spreading or separating of the same, without the use of fish or angle plates.

It is also an object of the invention to provide a novel lock for connecting the interengaged portions of the rail sections, the lock 20 serving as additional means for preventing relative lateral movement of the said sections.

Among other aims and objects of the invention may be recited, the provision of a 25 joint of the character mentioned with a view to compactness and in which the parts are few, the construction simple, the cost of production small, and efficiency and operation high.

All the foregoing together with additional 30 advantageous details and arrangement of parts of the preferred embodiment of my invention will be clear from the specific description hereinafter contained, when read 35 in connection with the accompanying drawing, forming parts thereof, wherein said embodiment of the invention is illustrated for the purpose of facilitating a full understanding of the present improvement.

In the drawing:

Figure 1 is a perspective of my improved joint;

Fig. 2 is a horizontal section therethrough;

Fig. 3 is a vertical section through the same, and

Fig. 4 is a perspective of the interengaging portions of the supporting rail ends disassembled.

Similar characters of reference are employed in all of the above described views to indicate corresponding parts.

Referring now more specifically to the several figures of the said drawing, there is 55 provided a plurality of rail sections 1 and 2, the adjacent extremities of which are pro-

vided with reduced portions 3 and 4 so formed as to permit interengaging thereof. A plurality of dove-tailed recesses 5 are formed within the upper face of the reduced portion 3 while at a point adjacent the inner extremity of the said reduced portion there is formed an inclined recess or pocket 6. Longitudinally disposed slidable locking bolts 7 having notches formed therein 60 are arranged within the lower reduced portion 3 and have their adjacent extremities extending into a pocket 8 in which there is positioned an expansible coil-spring 9, the opposite extremities or convolutions of 70 which engage the adjacent portions of the locking bolts, thus, serving as means for normally maintaining the same in their distended position. That portion of the tread of the rail section 1 adjacent its respective 75 reduced portion 3 is cut diagonally as at 10, for a purpose which will be subsequently apparent.

Upon the underface of the reduced portion 4 of the rail section 2, there are formed 80 a plurality of dove-tailed projections 11, the said projections being so formed and arranged as to permit the snug reception thereof in the recesses 5 formed in the reduced portion 3, while in certain of the sides thereof, pockets 12 are formed whereby the extremities of the slidable locking bolts 7 may be received therein. An extension 13 is formed upon the outer extremity of the reduced portion 4 and is of a shape to permit the same to be snugly received within the pocket 6 formed in the reduced portion of the rail section 1. The outer extremity of the said portion of the reduced portion 4 is cut at an angle complementary to the cutting of the portion of the tread of the rail section 1 whereby a close jointure between the same will be permitted.

It is to be noted that the dove-tailed recesses are of a size to permit loose engagement of the projections therein, thus allowing for expansion of the same. The slight space between the recesses and projections will permit the introduction of an implement thereinto, which, when engaged with 105 the notches in the slidable bolts may be moved to cause the retraction of the same, and, as a consequence, allowing the rail sections to be disengaged.

From the above, it will be understood that 110 by the beveled and undercut arrangement of the dove-tailed recesses and projections 5

and 11 respectively, the interengaging reduced portions 3 and 4 will be prevented from having excessive lateral movement and also from moving vertically. The 5 slideable locking bolts 7 which are engaged in the pockets formed in the dove-tailed projections 11 will serve as means for preventing lateral movement of the reduced portions in the direction taken to engage the reduced 10 portions and as a consequence, spreading of the rails due to relative lateral movement thereof will be prevented. Relative longitudinal movement of the rail sections will be also prevented due to the interlocking 15 engagement of the reduced portions of the same, while as above stated, vertical movement of the same will be prevented due to the combined efforts of the dove-tailed projections and recesses and the inclined pocket 20 6 and the head 13.

Obviously, the construction shown is capable of considerable modification and such modification as is within the scope of my 25 claims, I consider within the spirit of my invention.

I claim:

1. In a rail joint, the abutting ends of the rails being reduced and adapted to interengage, one of the reduced portions having 30 a dove-tail recess formed therein, the other of the reduced portions having a dove-tail projection, the projection being engageable with the recess of the opposite reduced portion; and a plurality of longitudinally 35 slideable locking bolts arranged in said projection in one portion and engageable with

the opposite sides of the recess of the other portion.

2. In a rail joint, the abutting ends of the rails being reduced and adapted to interengage, one of the reduced portions having dove-tailed recesses formed therein and an inclined pocket formed adjacent its inner extremity, the other of the reduced portions having dove-tailed projections thereon 40 and a beveled extension formed on the outer end thereof, said projections and extension being receivable in the recesses and pocket respectively, and longitudinally slideable locking means secured to one reduced portion and engageable with the dove-tailed projections of the other portion. 45

3. In a rail joint, the abutting ends of the rails being reduced and adapted to interengage, one of the reduced portions having dove-tailed recesses formed therein and an inclined pocket formed adjacent its inner extremity, the other of the reduced portions having dove-tailed projections and a beveled extension formed thereon, the projections and extension being engageable with the recesses and pocket of the opposite reduced portion respectively, the adjacent ends of the said portions of the abutting rail sections being beveled, and a plurality of 55 longitudinally slideable locking bolts arranged in one of the reduced portions and engageable with the dove-tailed projections of the other portion. 60

In testimony whereof I affix my signature 70 hereto.

JOSEPH A. PATTERSON.
